US00D613356S

(12) United States Design Patent
van Oorschot

(10) Patent No.: US D613,356 S
(45) Date of Patent: * Apr. 6, 2010

(54) BALL

(75) Inventor: Janneke van Oorschot, Herzogenaurach (DE)

(73) Assignee: Adidas International Marketing B.V., Amsterdam (NL)

() Term: 14 Years

(21) Appl. No.: 29/335,432

(22) Filed: Apr. 15, 2009

Related U.S. Application Data

(62) Division of application No. 29/327,904, filed on Nov. 14, 2008.

(30) Foreign Application Priority Data

Nov. 7, 2008 (EM) 001035562

(51) LOC (9) Cl. 21-02

(52) U.S. Cl. D21/713

(58) Field of Classification Search D21/707-714; 473/569-614; 40/327

See application file for complete search history.

(57) CLAIM

The ornamental design for a ball, as shown and described.

DESCRIPTION

FIG. 1 is a perspective view of a ball showing my new design; and,

FIG. 2 is side view of the ball in FIG. 1.

The broken line is included for the purpose of illustrating portions of the ball that form no part of the claimed design.
